UNITED STATES PATENT OFFICE.

JOHN KILLIP, OF ALLEGHENY, PENNSYLVANIA, ASSIGNOR OF ONE-HALF
TO HENRY CLAY BAIR, OF SAME PLACE.

STEAM-GOVERNOR.

SPECIFICATION forming part of Letters Patent No. 320,478, dated June 23, 1885.

Application filed August 12, 1882. (No model.)

To all whom it may concern:

Be it known that I, JOHN KILLIP, of Allegheny city, in the county of Allegheny and State of Pennsylvania, have invented a new and useful Improvement in Speed-Governors; and I do hereby declare the following to be a full, clear, and exact description thereof, reference being had to the accompanying drawings, forming part of this specification, in which—

10 Figure 1 is a plan view of my improved governor. Fig. 2 is a longitudinal vertical section on the line *x x*, Fig. 1. Fig. 3 is a vertical cross-section on the line *y y* of Fig. 2.

Like letters of reference indicate like parts in each.

The drawings illustrate my invention as applied to a horizontal governor.

Upon a suitable bed plate or casting, *a*, are standards *b b*, upon which in suitable boxes, *b'*, is a hollow shaft or spindle, *c*. On the shaft *c* is a pulley, *c'*, by means of which it is driven. At one end of the shaft *c* are two arms, *c'' c''*, extending longitudinally from the sides of the shaft, so as to form a recess or cavity, *c''*, between them. The outer end of each arm *c''* is bifurcated or recessed, forming two lugs, *c''*, on each. Between the lugs *c''* is a pin, *d*, upon which are pivoted the arms *d'* of the balls *d*.

Extending longitudinally through the shaft *c* is a sliding rod, *e*, which has a head or enlargement, *e'*, at its outer end between the arms *c''* of the shaft *c*. The outer end of the shaft *c* is bored out to a larger diameter for a short distance inward from the recess *c''*, as at *c''*, and is provided with a shoulder, *c''*, at the inner end of said bored-out portion. A strong spiral spring, *f*, is placed on the rod *e*, and bears at one end on the shoulder *c''* and at the other against the head *e'* of the rod *e*, or against a tension-nut, *e'*, placed thereon, and its function is to press the rod *e* outward.

Extending inward from the pivots *d'* and attached to the arms *d'* are short arms *d''*, which bear against the outer face of the head *e'*. On the inner ends of the arms *d''*, just back of the pivots *d'*, are projections or shoulders *d''*, which, when the balls are at rest, bear or rest upon the straight surfaces *c''* at the bottom of the recesses between the lugs *c''*. When the governor is at rest, the rod *e*, being forced out by the spring *f* and bearing against the arms *d''*, forces

the balls *d* inward toward the shaft *c*, as shown in Fig. 2, and causes the projections *d''* to rest against the surfaces *c''*. Thus the surfaces *c''* act as stops to limit the inward movement of 55 the balls.

At the other end of the rod *e* is a wrist, *e''*, which extends through the bearing *g*, and at its outer end is secured by a nut, *e''*. The bearing *g* is a yoke of rectangular form, and is 60 supported by a standard, *h*, the pin *h'* of which extends up through a slot, *g'*, in the bearing, which slot permits the bearing to slide longitudinally. The oil-hole in the cap *g''* is provided for the lubrication of the wrist *e''*. The 65 other end of the yoke or bearing is connected to the valve-stem *i'* by means of a nut, or in any other suitable way, as at *g''*. The valve-stem *i'* passes through a stuffing-box, *j*, which box is secured to the valve-box *k*. The valve *i* is fastened to the inner end of the valve-stem *i'*, and works in the valve-chamber *k'*, having its seat at *k''* around the steam-inlet *l*.

The valve is guided in its movement by an annular guide, *i''*, having radial arms *i''*, said 75 arms being recessed in the sides to permit the free passage of the stem through the chamber *k'* around and at the rear side of the valve *i*.

The exit-port is shown at *m*, and it is led back through the bed-plate or casting *a* to or near 80 to the center of the device, where the casing is provided with a flange, *m'*, by means of which it is attached in the required position. The purpose of leading the port *m* back through the leg or standard of the governor is to save 85 the expense of a separate attachment or to bring the standard at or near the center of gravity of the device, and thereby to sustain it in a better and more workmanlike way than would be the case if it was placed at the end 90 of the governor directly under the valve-chamber.

The operation of my improved governor is similar to that of other governors. An acceleration of the speed of the shaft *c* increases the 95 centrifugal action of the balls *d*, causing them to turn on the pivots *d'* and fly outward, and the arms *d''* to press on the end of the rod *e*, forcing it inward against the spring *f* and causing it to close the valve *i* sufficiently to 100 reduce the steam-opening, and thereby the velocity of the engine.

Among the other advantages of my improved governor are its simplicity of construction, durability, and efficiency.

By removing the caps b^2 and taking out the pin and washer e^3 the shaft c , rod e , and governor-balls may be removed from their bearings and taken apart for repairs.

This governor may be arranged vertically by using bevel or other suitable gearing for turning the shaft.

The rod e , while having no positive connection with the shaft c , is caused by the friction to rotate therewith, and hence it is necessary to form the bearing g with a journal-box, g^3 , in which the wrist e^2 revolves.

The stem i' of the valve i has a sliding motion, but does not rotate.

What I claim as my invention, and desire to secure by Letters Patent, is—

1. The combination of the rotatory shaft,

balls pivoted thereto having arms, central sliding rod against which the ends of the ball-arms bear, a slotted sliding bearing having a journal-box in one end, and a valve, the stem of which is connected to the said sliding bearing, substantially as and for the purposes described.

2. The combination of a rotatory longitudinally-moving stem of a steam-governor, a slotted sliding bearing, and the non-rotatory sliding stem of the valve which controls the admission of steam to the steam-engine, substantially as and for the purposes described.

In testimony whereof I have hereunto set my hand this 7th day of August, A. D. 1882.

JOHN KILLIP.
